FENCE

Otto R. Widman, Modesto, Calif.

Application January 25, 1954, Serial No. 28,654

Term of patent 14 years

(Cl. D28—1)

To all whom it may concern:

Be it known that I, Otto R. Widman, a subject of Sweden, residing at Modesto, in the county of Stanislaus and State of California, have invented a new, original, and ornamental Design for a Fence, of which the following is a specification, reference being had to the accompanying drawing, forming a part thereof.

Fig. 1 is a side perspective view of a fence showing my new design.

Fig. 2 is a sectional plan, on reduced scale, taken on line 2—2 of Fig. 1.

The end post shown in broken lines is for illustrative purposes only.

The fence is shown as broken away, or foreshortened, in order to indicate indefinite length.

The dominant features of my design reside in the portions shown in full lines.

I claim:

The ornamental design for a fence, as shown and described.
